(57) **CLAIM**

The ornamental design for a pizza dough mold, as shown
and described.

DESCRIPTION

FIG. 1 is a top plan view of the pizza dough mold showing
my new design; and,

FIG. 2 is a cross-sectional view thereof taken along line
2—2 of FIG. 1.

The broken line showing of the pedestal in FIG. 2 is for
illustrative purposes only and forms no part of the claimed
design.
